THREAD CONTROLLER FOR SEWING MACHINES

Frederick F. Zeier, Stratfield, Conn., assignor to
The Singer Manufacturing Company, Elizabeth,
N.J., a corporation of New Jersey

Application March 19, 1948, Serial No. 15,806

7 Claims. (Cl. 112—242)

1

This invention relates to sewing machines and more particularly to a thread-controller adapted for use in a sewing machine of the type disclosed in my copending application Serial No. 15,805, filed March 19, 1948.

The invention has for an object to provide an improved thread-controller which is conveniently accessible for threading.

Another object of the invention is to provide a thread-controller particularly adapted for a needle-feed chain-stitch machine in which the amount of looper travel is small compared to the amount of needle travel, the small looper travel making it desirable to have an efficient and accurate control of the looper-thread in order to insure the proper formation of the usual thread-triangle for entrance by the needle.

The invention also aims to provide a thread-controller which is adjustable to control its effect on the looper-thread during the critical portions of the stitch-forming cycle, and to control its effect on pulling off thread from the source of supply.

The foregoing and other objects and advantages of the invention will best be understood from the following description of an illustrative embodiment thereof shown in the accompanying drawings, in which:

Fig. 1 is a left side elevation, partly broken away, of a substantially complete feed-off-the-arm sewing machine embodying the invention.

Fig. 2 is a top plan view of a section of the laterally extending arm of the machine-frame with a portion thereof broken away to illustrate the actuating devices for the rock-shaft carrying the thread-controller.

Fig. 3 is a top plan view similar to Fig. 2, and showing the thread-controller at the beginning of its thread take-up stroke.

Fig. 4 is a top plan view similar to Fig. 3, but showing the thread-controller at the end of its thread take-up stroke, this view also illustrating the usual tension devices through which the thread travels prior to entering the thread-controller.

Fig. 5 is a perspective view with the cover-plate in section, showing in full lines the thread-guides and their supporting structure and in dotted lines the thread-controller arms and the carrier therefor.

Referring more in detail to the drawings, the improved thread-controller is shown as embodied in the sewing machine forming the subject of my copending U. S. Patent application Serial No. 15,805, filed March 19, 1948. The sewing machine

2

includes a frame comprising a standard 10 of a bracket-arm terminating in an overhanging head 11. Preferably integral with the front side of the standard 10 is the work-arm casting including an upper forwardly projecting arm 12, a laterally extending arm 13, and a vertically depending arm 14 carrying a horizontal work-supporting arm 15 disposed so that its free end underlies the head 11.

The stitch-forming mechanism of the present machine comprises a thread-carrying needle 16 carried by the lower end of a needle-bar 17 supported in said head 11 for endwise reciprocatory work-penetrating and sidewise vibratory work-feeding movements. Cooperating with the needle 16 in the formation of two-thread chain-strokes is a thread-carrying looper 18 mounted upon a looper-carrying bar 19 extending endwise of said work-supporting arm 15. Assisting the needle and looper in stitch-formation is a movable spreader 20 which is actuated to swing transversely of the path of travel of the looper to engage and distend the looper-thread to form the usual triangle with the previous needle-thread-loop for entrance by the descending needle. Supplementing the needle 16 in feeding the work endwise of the work-supporting arm 15, is a lower four-motion feed-dog 21 which is apertured in the usual manner to receive and back-up the needle 16 during the work-feeding movement of the needle. Opposed to the feed-dog 21 is the usual presser-foot 22 carried on the lower end of a spring-biased presser-bar 23 endwise slidably journaled in the head 11.

As clearly shown and described in my copending application referred to above, the looper 18 derives its endwise loop-seizing and -shedding movements and its sidewise "needle-avoiding" movements from mechanism disposed within the vertically depending arm 14. This mechanism includes an actuating rock-shaft 24 journaled in bearing bushings 25 and 26 fixed in the top and bottom walls of the arm 14. The shaft 24 is operatively connected at its lower end, by suitable means, to the looper-bar 19 and has clamped to it adjacent its upper end a rock-arm 27 (Fig. 2) which is connected by a short pitman 28 to a crank 29 formed on a rotary counter-shaft 30 journaled in the laterally extending arm 13. Rotation of the crank 29 will effect an oscillation of the rock-shaft 24, which in turn will impart an endwise movement to the looper-bar 19 giving to the looper 18 its loop-seizing and -shedding strokes.

In chain-stitch sewing machines it is preferable to operate the looper-thread controlling

means from the looper-actuating mechanism in order that exact timing between the looper and the thread-controller can be conveniently obtained. To that end, the present thread-controller is adapted to be fastened on the exposed upper end of the looper-actuating rock-shaft 24. Referring to Fig. 1, it will be seen that the means for securing the thread-controller on the rock-shaft 24 includes a pair of opposed clamp-jaws in the form of a thrust-washer 31 and a clamp-disk 32. Extending through aligned apertures in the clamp-disk 32 and thrust-washer 31 is a clamp-screw 33 threaded into the tapped end of the rock-shaft 24. Secured between the clamp-jaws 31 and 32 are a pair of thread-engaging members 34 and 35, each of which is adapted to be endwise adjusted relative to the axis of the rock-shaft 24 by loosening the clamp-screw 33. It will be understood that when the clamp-screw 33 is loose, the clamp-disk 32 also can be angularly or circularly adjusted about the axis of the shaft 24. The thread-engaging member 34, which is the shorter of the two members, is bent upwardly at its free end to provide a vertically disposed thread-engaging limb 36 adapted to contact the looper-thread T^L passing between a stationary thread-guide 37 and the upper end of a thread-guiding device 38 secured in a channel 39 formed in the outer wall of depending arm 14. The longer thread-engaging member 35 is also bent upwardly at its free end to provide a thread-engaging limb 40 adapted to contact the looper-thread T^L passing between a stationary thread-guide 41 and the thread-guide 37, the upper end of the limb 40 terminating in a reversely bent tail 42 which overhangs the looper-thread or threads and prevents them from sliding off the upper end of the thread-engaging limb 40 during the operation thereof.

The two stationary thread-guides 37 and 41 are adjustably secured by means of the screws 43 and 44 upon a supporting angle-bracket 45 which is secured to the side wall of the depending arm 13 by the screws 46 threaded into said arm. A suitable swing-up guard- or cover-plate 47 is hinged to the angle-bracket 45 and when the cover-plate is in its lowered or closed position, as shown in Fig. 1, the cover-plate serves to guard the operator from inadvertently contacting the rapidly moving take-up arms 34 and 35.

Operation

When the looper thread-controller is at the beginning of its take-up stroke, which position is illustrated in Fig. 3, the looper 18 is advancing in its loop-seizing stroke endwise of the work-supporting arm 15 in a direction toward the depending arm 14. During this stroke of the looper, slack looper-thread is produced adjacent the looper, and to absorb this slack thread and maintain an accurate control on the looper-thread, the thread-engaging member 34 is caused to swing from the position shown in Fig. 3 to that shown in Fig. 4. In moving to the position shown in Fig. 4, a bight is formed in the looper-thread T^L between the thread-guide 37 and the upper end of the thread-guiding device 38, the thread forming the bight being drawn back from that portion of the thread leading to the looper. By effecting the proper relative adjustment between the thread-engaging member 34 and the thread-guide 37, the looper-thread is so controlled that during the entire loop-seizing stroke of the looper 18 and while it is dwelling at the end of its loop-seizing stroke, the looper-thread is held suffi-

ciently taut that it is maintained in position to be unerringly seized by the spreader 20 as the latter moves transversely of the looper to spread the thread-triangle for entrance by the descending needle.

In chain-stitch machines it is customary to provide means for drawing thread from the supply during each stitch-forming cycle, which thread is to be used in the subsequent stitch-forming cycle. The thread-engaging member 35 of the present device is provided for that purpose. In operation, the thread-engaging arm 35 swings between the two stationary thread-guides 37 and 41, forming a bight in the thread as shown in Fig. 4. The thread forming the bight is pulled from the supply through the usual tension device 48 which is used to properly tension the thread in its passage to the looper. It will be observed in Fig. 3 that the vertical limb 40 of the member 35 is spaced from the looper-thread T^L . This is purposely done so that the thread pull-off action will occur only during the latter part of the active stroke of the thread-engaging arm 35.

From the foregoing, it will be understood that during the initial portion of the active stroke of the thread-controller, only one of the thread-engaging members, namely, member 34, contacts the looper-thread T^L and not until all the lost motion between the thread-engaging member 35 and the looper-thread is taken up, do both of the thread-engaging members 34 and 35 operate on the looper-thread simultaneously. As shown in Fig. 4, at the end of the active stroke of the two thread-engaging members 34 and 35, member 34 cooperating with the fixed thread-guide 37 forces the looper-thread to undergo a sharp bend about the thread-guide 37 which results in a snubbing action on the looper-thread and prevents any accidental movement of the thread toward the looper. When the snubbing action on the thread occurs it is at a critical time in the stitch-forming cycle when the spreader is operating to dis-tend the looper-thread limb of the thread-triangle. The snubbing action on the thread at this time is desirable because the looper-thread is thereby accurately controlled and maintained elevated within the range of action of the spreader device.

Having thus set forth the nature of the invention, what I claim herein is:

1. In combination with a threaded reciprocating needle and a complementary thread-carrying looper, looper-operating mechanism including an actuating rock-shaft, of a thread-controlling mechanism including spaced thread-guides through which the looper-thread passes, and movable thread-engaging members connected directly to said actuating shaft and disposed so that one of said thread-engaging members operates between the spaced thread-guides and the other operates outside the field between said thread-guides.

2. A sewing machine having, a frame including an overhanging head, a work-supporting arm, and a depending arm carrying said work-supporting arm, an endwise reciprocating needle carried by said head, a thread-carrying looper supported by said work-supporting arm, mechanism for operating said looper including an actuating shaft journaled in said depending arm and having one of its end-portions exposed, spaced thread-guides mounted on said depending arm, and a thread-engaging device mounted on the exposed end-portion of said actuating shaft and

arranged to contact the thread adjacent said thread-guides.

3. A sewing machine having, a frame, stitch-forming mechanism including a threaded needle and a complemental thread-carrying looper, looper-operating mechanism including an actuating shaft journaled in said frame, and a thread-controlling mechanism including spaced thread-guides, a pair of movable thread-engaging members disposed to contact the looper-thread adjacent said thread-guides, and a clamp device for securing said thread-engaging members to said actuating shaft, said clamp device providing for adjustment of said members endwise of themselves and circularly about the longitudinal axis of the actuating shaft.

4. In combination with stitch-forming devices including a threaded reciprocatory needle and a complemental thread-carrying looper, operating means for one of said stitch-forming devices including an actuating rock-shaft, of a thread-controlling mechanism including spaced thread-guides, and a pair of oscillatory thread-engaging members connected directly to said actuating shaft and disposed to operate upon the thread adjacent said thread-guides, said thread-engaging members being relatively arranged so that one is acting on the thread during a greater portion of its oscillation than is the other thread-engaging member.

5. A sewing machine having, a frame including an overhanging head and a work-arm portion including a laterally extending arm, a depending arm carried by said laterally extending arm, and a work-supporting arm carried by said depending arm, an endwise reciprocatory needle carried by said head, a thread-carrying looper supported by said work-supporting arm, mechanism for actuating said looper including an actuating shaft journaled in said depending arm lengthwise thereof and having its upper end-portion exposed at the top of the laterally extending arm, spaced

thread-guides, and a thread-engaging device mounted on the exposed end-portion of said actuating shaft and arranged to contact the thread adjacent said thread-guides.

5 6. Thread-controlling mechanism for sewing machines, comprising, a thread-tension device, spaced thread-guides disposed to successively direct a thread leading from said tension-device, a thread pull-off member having its effective thread-engaging path of movement between said thread-guides, a thread take-up member having its effective thread-engaging path of movement at the side of said thread-guides remote from said tension-device, means for vibrating said pull-off and take-up members about a common axis, and means providing for relative adjustment of said members radially of said axis.

10 7. In combination with stitch-forming devices including a threaded reciprocatory needle and a complemental thread-carrying looper, operating means for one of said stitch-forming devices including an actuating rock-shaft, of a thread-controlling mechanism including spaced thread-guides, and a pair of movable thread-engaging members connected directly to said actuating shaft and disposed to operate upon the thread adjacent said thread-guides, one of said thread-guides and one of said thread-engaging members being relatively arranged so that in one extreme 15 position of movement of said thread-engaging member the thread is snubbed between said member and said thread-guide and thereby effectively locked against accidental movement.

30 FREDERICK F. ZEIER.
